FLEXIBLE STRAND CONVEYOR SYSTEM WITH COMPENSATING SPREADER BAR ASSEMBLY
Roy F. Lo Presti, Chicago, Ill., assignor to Goodman Manufacturing Company, Chicago, Ill., a corporation of Illinois

Filed Sept. 9, 1958, Ser. No. 759,879
3 Claims. (Cl. 198—184)

This invention relates generally to conveyors and is particularly directed to means for maintaining the belt of a flexible strand conveyor centrally entrained along the roller assemblies of the conveyor under all load conditions.

Flexible strand conveyors of the type illustrated in the Craggs et al. Patent No. 2,773,257 are coming into widespread use due to their many inherent desirable features including ruggedness, ease of assembly, accuracy of adjustment and low cost of installation, operation and initial investment. In general, these conveyors are composed of a pair of generally parallel flexible strands, such as wire ropes or the like, trained along a course, such as a mine run, and are supported at spaced intervals by ground engaging supports. The supports may be connected directly to the ground or to some other substantially rigid support structure, and may be spaced at intervals varying from 10 to 30 feet depending on a number of factors. Ten feet is a spacing commonly used in the coal mining industry for example.

A plurality of roller assemblies are interposed between adjacent ground engaging supports which determine the nominal gauge of the conveyor and form a bed for the flexible conveying belt. These roller assemblies vary widely, but a typical assembly may comprise a center, primary belt training roller pivotally connected to a pair of side or wing rollers. The wing rollers in turn are adapted to be connected to the flexible strands at their outer ends by means of clamps, or other suitable securing means.

In operation, a belt is trained along the roller assemblies and caused to run centered by means of preliminary adjustments. For example, if a belt tends to run high to one side, this tendency may be remedied by merely canting the opposite end of the roller assembly back towards the direction of travel.

In this type of conveyor it is not absolutely essential that a ground engaging support be employed at the beginning and end of each spaced interval. It is frequently sufficient in coal mining applications for example, to utilize support stands placed at 20 foot intervals. Rigid spreader bars located half way between supports may then be suspended from the strands to maintain the proper strand spacing. The use of spreader bars cuts the cost of the final assembly considerably, since a support stand is a more complex structure requiring additional fabricating operations.

When spreader bars having a length substantially equal to the distance between suspension points (i.e., gauge) at the support stands are utilized, it not infrequently happens that rather erratic belt training results follow due to the catenary sag of the strands. This inherent downward droop of the strands is increased by the weight of the roller assemblies which also tend to pull the ropes closer together. The roller assemblies farthest from the ground engaging supports will be lower than those next adjacent the supports. In a conveyor system having four roller assemblies suspended from flexible strands 48 inches apart between a pair of ground engaging supports, there may be as much as an inch difference in height between the primary training rollers of the roller assemblies located midway between these supports and those located adjacent the supports. Conventional spreader bars having

2

a span equal to the span between suspension points at the support stands maintain substantially uniform spacing of the strands but do not counteract the catenary sag.

These erratic results may be illustrated by the following example. A belt may be trained with a load on it so that it runs straight down the middle of the roller assemblies, but when the load is removed the belt may run wildly off to one side or the other. This can easily occur when the rollers next adjacent the rigid ground engaging support structures are cocked out of line, for example, to the right in the direction of travel, and more remote roller assemblies are cocked out of line in the opposite direction. When the belt is loaded it will press firmly on all the rollers and the detraining tendencies cancel one another. As soon as the load is taken off the belt, however, the belt rises and may be supported only by those roller assemblies next adjacent the ground engaging support structures. The left detraining tendency of the lower roller assemblies is thereby removed and there is no counteracting forces preventing detraining of the belt to the right.

Accordingly, a primary object of the invention is the provision of means for maintaining the primary training rollers of a flexible strand conveyor system at substantially the same level.

Another object is the provision of means for maintaining good belt training contact of roller assemblies under all load conditions.

Another object is the provision of means for increasing the belt training effect of a flexible strand conveyor by decreasing the included angle between the center primary training roller and the wing rollers of the roller assemblies to thereby decrease the unsupported gap of belt between the center and wing rollers.

Another object is the provision of an elongated, substantially rigid spreader bar capable of being suspended from the flexible strands of a flexible strand conveyor and out of contact with the ground which will maintain the level of the primary training roller of the roller assemblies next adjacent it at a level substantially equal to the level of the primary training rollers of roller assemblies next adjacent the ground engaging support stands.

Another object is the provision of a conveyor system comprising a pair of flexible strands suspended between a pair of ground engaging support structures, a plurality of roller assemblies suspended from the strands and a spreader bar assembly connected across the strands for counteracting the catenary sag of the strands between the ground engaging supports to maintain the training rollers of the roller assemblies at a substantially uniform height.

Yet another object is the provision of a spreader bar assembly for maintaining the training rollers of roller assemblies in a flexible strand conveyor system at a substantially uniform height which is rugged, easy to install, and inexpensive to manufacture.

The invention is illustrated more or less diagrammatically in the following drawings wherein:

FIGURE 1 is a plan view of a portion of a flexible strand conveyor utilizing a spreader bar assembly of the present invention;

FIGURE 2 is an elevation view taken along the line 2—2 of FIGURE 1; and

FIGURE 3 is a front view of a pair of roller assemblies taken along the line 3—3 of FIGURE 2 showing the relationship of the assemblies superimposed upon one another.

Like reference numerals refer to like parts throughout the following description.

Referring now to FIGURE 1, a portion of a flexible strand conveyor system with the belt omitted for clarity

is shown as comprising a pair of ground engaging supports 1, having base or feet 2 adapted to rest upon the floor of a mine run or the like. A vertical support stand which may or may not be adjustable is indicated at 4 and a rigid cross member 5 maintains the support stands in spaced relationship. A return roller assembly is indicated generally at 6 for supporting the conveying belt on its return reach. A pair of U-shaped members 7 and 8 are secured to the top of the vertical support stand 4 and form support or suspension points for a pair of flexible strands 9 and 10 received therein. Any suitable means may be employed to clamp the flexible strands to the support members 7 and 8. The vertical support stands may be so designed that the vertical members 4 will rock in order to compensate for the stresses placed upon the support stands by the approach and retreat of a load to the stand.

Next adjacent the ground engaging support structure 1 is an upper roller assembly A including a primary center belt training roller 12 pivotally connected at its ends to wing rollers 15 and 16. The wing rollers in turn are connected at their outer ends as at 17 and 18 by suitable clamps or other means to the flexible strands 9 and 10.

Spaced downstream in the direction of the arrow from the first roller assembly in FIGURE 1 is a second lower roller assembly B consisting of a primary belt training center roller 12' pivotally connected to end or wing rollers 15' and 16'. The outer ends of the wing rollers are in turn connected to flexible strands 9 and 10 as at 17' and 18'. While the details of the roller assemblies utilized may vary widely it will be understood that in any particular conveyor system, the roller assemblies will be identical.

Located further downstream as viewed in FIGURE 1 is a spreader bar assembly 20. The spreader bar assembly includes an elongated substantially rigid body having a dished central portion 22, see FIGURE 2, integrally and rigidly connected to end or flank portions 23 and 24. These flank portions terminate in attaching means 25 and 26 which are adapted to receive the flexible strands 9 and 10 and may be secured thereto by any suitable means.

The distance between the attaching means 25 and 26 of the spreader bar is somewhat longer than the distance between the support points 7 and 8 at the ground engaging support structure.

Referring now specifically to FIGURE 2, the ground level is indicated at 3. A conveyor belt having an upper conveying reach 30 and a lower return reach 31 is shown in outline supported upon the roller assemblies and the return roller respectively.

Since the downward sag of the strands will be at a maximum at a point substantially midway between the ground engaging supports, the center training roller 12' of the lower roller assembly B will be substantially lower than the primary training roller 12 of the upper roller assembly A. In a conventional 48 inch conveyor assembly the difference in height between rollers 12' and 12 may be on the order of one inch. By interposing the elongated spreader bar 20, the primary training roller 12' of lower assembly B is brought up substantially to the level of the primary training roller 12 of upper assembly A. The amount of overhang required is not great, and in a 48 inch installation a spreader bar having a two inch overhang on each side is sufficient to level out the rollers.

This effect is best illustrated in FIGURE 3 wherein the position of lower roller assembly B has been superimposed upon that of upper roller assembly A looking in the direction of the arrows 3-3 of FIGURE 2. The outline of the center rollers 12 and 12' fall substantially upon one another whereas the outlines of the wing rollers are displaced with respect to one another, the wing roller of upper assembly A being positioned slightly upward

from the wing rollers of lower assembly B. The distance between the attaching points 17' and 18' will be somewhat greater than that between 17 and 18 because the lower assembly B is substantially closer to the spreader bar than the upper assembly A.

Another important advantage of the invention is the fact that the belt training effect is improved under all load conditions. For example, conveyor belts conventionally used in conveying installations such as coal mines and the like are usually made of rubber with either a plastic or metal core. Although sufficiently flexible to form a trough, they have a certain amount of inherent stiffness which causes a bridging effect when the belt is supported at two relatively closely spaced support points vertically offset from one another. Two such points would be represented for example by the wing and center rollers of a roller assembly of the present invention. Directly over the pivot point between the rollers, a portion of the belt will be unsupported and hence receives no training effect. The greater the included angle between the wing roller and the center roller, the greater the unsupported span of belt will be. In a 48 inch conveyor for example, utilizing a conventional rubber reinforced belt and a 52 inch spreader bar, the included angle at the upper roller assembly A may be on the order of 24° and the length of contact between the belt and the centering roller 12 may be on the order of 6 1/4 inches. In the same installation the included angle at the lower roller assembly B will be approximately 18° and the length of contact between the belt and centering roller 12' will be approximately 8 3/4 inches.

Although a preferred embodiment of the invention has been shown and described it should be understood that the invention is not limited to the specific details here disclosed. For example, although the spreader bar assembly 20 has been shown as being downwardly concave to clear the bottom of the belt it might be entirely feasible, especially in installations in which the material to be conveyed will always be at a uniform depth such as slurries, to reverse the spreader bar so that in effect it forms an arch under which the belt passes. This may be particularly advantageous in installations wherein there is plenty of head room but small clearance between the bottom of the roller assemblies and the ground or other protruding objects. Similarly, although the attaching means 25 and 26 have been shown as integral with the spreader bar 20, it may be advantageous to make them adjustable to thereby vary the length of the bar. Accordingly, the invention should be limited only by the scope of the following appended claims.

I claim:

1. A flexible strand conveyor system including a pair of generally parallel flexible strands trained along a mine run or the like, a plurality of support structures located at intervals along the strands, the strands being suspended from the support structures, a plurality of roller assemblies carried by the strands between adjacent support structures, said assemblies having at least a primary training roller for carrying a flexible moving belt, and a flexible strand catenary sag compensating spreader bar for elevating the primary training roller of a first roller assembly to substantially the level of the primary training roller of a second roller assembly, said second roller assembly being located nearer a support structure than the first roller assembly, said bar being longer between the points at which it engages the flexible strands than the distance between the flexible strands at the support structures, said bar having a concave shape to thereby clear a belt traveling over the assemblies in all conditions of load.

2. A flexible strand conveyor system including a pair of generally parallel flexible strands trained along a mine run or the like, a plurality of support structures located at intervals along the strands, the strands being suspended

from the support structures, a plurality of roller assemblies carried by the strands, said assemblies having at least a primary training roller for carrying a flexible moving belt, and a flexible strand catenary sag compensating spreader bar for elevating the primary training roller of a first roller assembly to substantially the level of the primary training roller of a second roller assembly, said second roller assembly being located nearer a support structure than the first roller assembly, said bar being longer between the points at which it engages the flexible strands than the distance between the flexible strands at the support structures, said bar having a concave shape to thereby clear a belt traveling over the assemblies in all conditions of load.

10

3. The flexible strand conveyor system of claim 2 further characterized in that there are four roller assemblies located between adjacent support structures, the interval between adjacent roller assemblies being substantially equal, said bar being secured to the flexible strands between the middle two roller assemblies.
